Specification for Design.

Patented Apr. 26, 1921.

Application filed June 16, 1920. Serial No. 389,504. Term of patent 14 years.

To all whom it may concern:

Be it known that I, HOWARD G. SWARR, a citizen of the United States, residing at Lancaster, Lancaster county, Pennsylvania, have invented a new, original, and ornamental Design for a Boot or Shoe Heel, of which the following is a specification, reference being had to the accompanying drawing, forming part thereof.

The drawing is a perspective view of a heel embodying the design.

I claim:

The ornamental design for a boot or shoe heel, as shown.

In testimony whereof, I have hereunto set my hand.

HOWARD G. SWARR.
